UNITED STATES PATENT OFFICE.

STEPHEN DE AYALA, OF BROOKLYN, NEW YORK, ASSIGNOR TO SARGENT & COMPANY, OF NEW HAVEN, CONNECTICUT, A CORPORATION OF CONNECTICUT.

GROOVING-PLANE.

1,158,648.

Specification of Letters Patent.

Patented Nov. 2, 1915.

Application filed September 17, 1912. Serial No. 720,800.

To all whom it may concern:

Be it known that I, STEPHEN DE AYALA, a citizen of the United States, residing in Brooklyn, county of Kings, and State of New York, have invented certain new and useful Improvements in Grooving-Planes, of which the following is a full, clear, and exact description.

This invention relates to grooving planes 10 and more particularly to planes adapted to cut rather shallow V-shaped grooves.

The improved plane is especially adapted for cutting series of intersecting grooves on surfaces of rather extended area in order to 15 give the ornamental appearance of paneling composed of a plurality of separate blocks.

The object of the invention is to provide an improved arrangement of the cutting 20 mechanism; to furnish an improved means of adjustment between the cutting mechanism and the sole of the stock; and to provide improved means for supporting and 25 adjusting the gage or fence by which the plane is guided in a predetermined path, said gage or fence being adapted for guidance in a completed groove during the operation of cutting the next groove.

To these and other ends, the invention 30 consists in the novel features and combinations of parts to be hereinafter described and claimed.

In the accompanying drawings, Figure 1 is a side elevation of a plane embodying my 35 invention, Fig. 2 is a similar elevation from the opposite side, Fig. 3 is a front end elevation, Fig. 4 is a rear end elevation with the sole plate and gage in different adjustments from those in Fig. 3, Fig. 5 is a bottom plan view of the plane, Fig. 6 is a detail section on line 6—6 of Fig. 4, Fig. 7 is a vertical longitudinal section of the plane, Fig. 7^A is a detail section on line 7^A—7^A of Fig. 7, Fig. 8 is a horizontal section on line 40 8—8 of Fig. 1, Fig. 9 is a top plan view of the sole plate, detached, Figs. 10 and 11 are details of the gage locking mechanism, the first showing one of the gage pins released and the second showing it locked in position, Figs. 12 and 13 are sections on lines 45 12—12 and 13—13 respectively of Figs. 10 and 11, Fig. 14 is a detail of the locking plate of the gage mechanism, Fig. 15 is a detail of one of the gage supporting pins, and Fig. 16 is a detail of one of the bits or 55 cutters.

Referring to the drawings the stock, indicated at 20, may be of wood, having a metal insert or frame 21 at the base thereof to support the cutters 22. Below the base portion 60 of the frame or insert 21 is a sole plate or bed piece 23, adjustable vertically by means to be hereinafter described, and having a slot or throat 24 through which the cutting edges of the bits 22 project downwardly, as 65 shown in Fig. 7. The bits or cutters 22 are arranged in V-fashion, each being clamped in an inclined position relative to the longitudinal plane of the device, against bearing portions 25 at the respective sides of the 70 frame or insert piece 21, so that the cutter blades converge downwardly. These blades are adjustably secured in place by means of screws 26 engaging slots 27 in the respective blades or bits, as shown in Fig. 7^A. At their 75 lower portions the bits 22 are provided with beveled cutting edges 28 inclined downwardly from the front of the plane toward the rear thereof, as shown in Fig. 7, and the lowermost corners of points of the two bits 80 which lie rearwardly with respect to the stock are arranged in contact with each other as shown at 29 in Fig. 8. From their rear points of contact the beveled cutting edges 28 of the bits diverge forwardly and 85 upwardly as shown in Figs. 7 and 8. This arrangement of the cutters has been found to give excellent results in actual practice, as the sharp edges of the bits produce a 90 shearing cut and their contacting points at the rear cut the wood sharply and uniformly to produce a V-shaped groove.

The depth of the cut is regulated by adjusting the sole plate 23 in a vertical direction so that the contacting points of the bit 95 edges extend below the lower surface of the sole plate to a greater or less extent. The sole plate is preferably adjusted in this manner by means of separate adjusting devices at the respective ends of the plane, as 100 shown. In the embodiment illustrated, the front adjusting device comprises a thumb screw 30 rotatable in the front or nose portion of the stock as shown in Fig. 7, and held from vertical displacement in the stock by 105 means of a small plate 31 set in a kerf of

the stock, and below which, is a check nut 32 threaded on the shank 33 of the thumb screw 30. This shank 33 engages the interior threads of a nut 34 formed on or secured to the upper surface of the sole plate at the front end thereof, so that by rotating the thumb screw 30 in one or the other direction the front end of the sole plate may be raised or lowered respectively. The rear adjusting device for the sole plate comprises a tubular shank 35 having a thumb piece 36 and provided with interior threads which engage a threaded shank 37 secured to or integral with the rear end of the sole plate and rising therefrom. The tubular thumb screw 35, 36 is prevented from longitudinal displacement by means of a plate 37 set in a kerf of the stock and engaging a notch in the tubular portion 35 as shown in Fig. 7, said tubular portion being freely rotatable at both ends in suitable sockets 38, 39 provided in the body portion of the stock. By suitable manipulation of the front and rear adjusting devices for the sole plate 23, said sole plate may be adjusted vertically in parallelism with the bottom part of the stock proper.

40 indicates a gage or fence adapted to project downward into a groove cut by the 30 plane in order to guide the latter in cutting the next groove. This gage or fence 40 is arranged parallel to the stock at one side thereof as shown in Figs. 3 and 4 and is constituted by a flat plate adjustable laterally toward and away from the side of the plane proper. The adjusting mechanism for the gage device comprises supporting pins 41 extending through tubular sockets 42 formed in the insert or flame 21, as 35 shown in Figs. 7 and 8. The pins 41 are each provided at one end with a manipulating head 43 and at the opposite end each of said pins is provided with an interiorly threaded socket for the reception of a screw 44 passing through the gage plate and having a head 45 abutting the same. By screwing in or out the screws 44, the position of the gage plate may be varied relatively to the ends of its supporting pins 41, as shown 45 by a comparison of Figs. 3 and 4, and a further adjustment is provided, in order to bring the adjustment to a nicety, by having the pins 41 adjustable longitudinally in their sockets *i. e.* transversely of the plane. 50 For this purpose each pin is provided with a plurality of annular grooves 46, and a locking plate 47 (Figs. 8 and 14) is adapted to coöperate with the grooves 46 of both pins in order to lock both pins simultaneously in a predetermined transverse adjustment in respect to the plane. The tubular sockets 42 for the supporting pins are extended out of the stock 20 at one side of the latter, as shown at 48 in Figs. 12 and 13, 55 and the portions 48 are slotted at one or

more points in their circumference as shown at 49 in Fig. 12. The locking bar or plate 47 is provided with keyhole slots 50 fitted over the portions 48 by placing the enlarged portions of said keyhole slots in register with the latter, and when in such position a longitudinal movement of the locking bar 47 will cause the portions of the bar at the smaller ends of the slots to take into the notches or slots 49 in such a manner as 75 to engage certain of the grooves 46 of the pins 41, thereby locking said pins against longitudinal movement, as shown in Fig. 13. The bar 47 may be manipulated by means of finger pieces 51 extending upward 80 therefrom, and when the bar has been moved to its released position (Fig. 12), in which the enlarged ends of the keyhole slots surround the ends of the sockets 42, the supporting pins 41 of the gage or fence may be 85 moved transversely of the plane to the desired position by appropriate manipulation of the heads 43 of said pins which are located on opposite sides of the plane with respect to the gage or fence. By providing an adjustment of the gage plate relative to the supporting pins and an adjustment of the supporting pins relative to the stock, a very nice and accurate adjustment of the gage may be obtained, as will be obvious. 90

The operation of the device will be more or less obvious from the foregoing description. The cutters or bits 22 after being clamped in place by means of the screws 26 are not usually adjusted as the device is 100 used, the depth of cut being easily regulated merely by the vertical adjustment of the sole plate with respect to the stock or body proper. In practice the plane is usually employed for cutting a number of parallel 105 grooves and when the desired distance between the grooves has been ascertained it is merely necessary to adjust the gage 40 in the manner hereinbefore described in such a manner as to make the distance from the 110 gage to the contacting point of the cutters equal to the desired interval or space between the grooves. When it is desired to change the spacing of the grooves, the locking bar 47 and supporting pins 41 are 115 manipulated in the manner hereinbefore described.

Of course, I do not wish to limit myself to a construction in which the body or stock is made of wood as the entire device may be made of metal without departing from the general features of the construction. While the foregoing description is a detailed one in so far as it concerns the particular form of my invention selected for 120 illustration, it will be understood that many variations of the construction may be adopted without digressing from my inventive idea as expressed in the claims. 125

I will not claim herein the features of the 130

adjustable sole plate and the gage attachment inasmuch as these subjects matter must be claimed in divisional applications.

What I claim is:

- 5 1. In a grooving plane, the combination of a stock having an opening therein with downwardly converging walls or surfaces at opposite sides of the longitudinal median line of the stock, and bits or cutters clamped 10 on said surfaces and having forwardly and upwardly diverging cutting edges to produce the groove by a shearing cut; substantially as described.
- 15 2. In a grooving plane, the combination of a stock, and separate bits or cutters mounted on the respective sides of the longitudinal median line of the stock, and having forwardly and upwardly diverging cutting edges to form the groove by a shearing 20 cut; substantially as described.
- 25 3. A grooving plane having separately adjustable bits or cutters arranged in V-fashion to cut a V-shaped groove with a shearing cut; substantially as described.
- 30 4. In a grooving plane, a stock, and bits or cutters arranged on opposite sides of the median line of the stock and converging downwardly; substantially as described.
- 35 5. In a grooving plane, bits or cutters having cutting edges contacting toward the rear of the plane and diverging toward the front of the plane; substantially as described.
- 40 6. In a grooving plane, bits or cutters arranged in the form of a V the plane of which extends transversely across the stock, with the rear ends of the cutting edges of said bits or cutters substantially in contact with each other and the front ends separated; substantially as described.
- 45 7. In a grooving plane, bits or cutters arranged in V-fashion, said cutters lying on opposite sides of a longitudinal median line or axis of the plane and having beveled cutting edges diverging from each other toward the front of the plane; substantially as described.
- 50 8. In a grooving plane, bits or cutters ar-

ranged in the form of a V, the plane of which extends transversely of the stock, the cutting edges of said bits or cutters diverging forwardly and upwardly; substantially as described.

55 9. In a grooving plane, bits or cutters arranged in the form of a V, the plane of which extends transversely of the stock, the cutting edges of said bits or cutters diverging forwardly and upwardly and being in contact at their rear extremities; substantially as described.

60 10. In a grooving plane, the combination of a stock, bits or cutters mounted in said stock in the form of a V, the plane of which extends transversely of the stock, the cutting edges of said bits diverging upwardly, and means associated with each bit to clamp 65 it in different adjustments; substantially as described.

70 11. An implement of the character described, comprising a grooving plane having a stock provided with a bearing portion adapted to rest on the material to be operated upon, and a cutter carried by the stock having a shearing edge facing forwardly of the implement and extending downwardly and rearwardly therefrom, substantially as 75 described.

80 12. An implement of the character described, comprising a grooving plane having a stock provided with a bearing portion adapted to rest on the material to be operated upon, and a pair of cutters carried by the stock having shearing edges facing forwardly of the implement and extending downwardly and rearwardly therefrom, said cutting edges occupying a rearwardly converging relation to each other substantially as described.

In witness whereof, I have hereunto set my hand on the 11th day of Sept., 1912.

STEPHEN DE AYALA.
